UNITED STATES PATENT OFFICE.

ELLSWORTH B. A. ZWOYER, OF PERTH AMBOY, NEW JERSEY, ASSIGNOR TO THE GENERAL FUEL BRIQUETTE CORPORATION, OF NEW YORK, N. Y., A CORPORATION OF NEW YORK.

PROCESS AND APPARATUS FOR BRIQUETTING.

Application filed June 6, 1925. Serial No. 35,496.

This invention relates to the agglomerating or compacting of loose materials such as coal dust, flue dust, or the like, into briquettes and has for its principal object 5 to improve upon the methods and apparatus heretofore employed for this purpose whereby greater uniformity in the treatment of the material is obtained and the quality of the resultant product is improved. 10 In the briquetting of loose material, it is customary to employ a liquid reagent or binder which is mixed with the loose material before subjecting the material to the briquetting pressure. Heretofore it has been 15 the practice to employ a pump for withdrawing the liquid binder from storage tanks and delivering it to be mixed with the loose material, the flow of the liquid being controlled by a manually operated valve. 20 provided in the delivery line of the pump. This practice is not entirely satisfactory because of the difficulty in uniformly regulating the flow by a hand valve. This difficulty is further increased by the back pressures built up, especially when gummy substances are employed as binders and when 25 the valve is throttled. As these back pressures cause variations of the flow which can not be readily detected either by observation of the stream delivered by the pump or by the appearance of the briquettes, the briquettes produced are sometimes of inferior 30 quality. 35 As a matter of practical importance, smaller departures from the proper predetermined amount of binder fed are more objectionable than larger variations, because the larger variations are much more readily detected. For example, assuming that the 40 binder should form 6% of the body of a given briquette, if the flow of the binder is reduced so that only 3% is delivered this variation could be immediately discovered 45 because it would be impossible with such a small proportion of binder for the briquetting press to effect the compacting of the material into briquettes of the proper consistency. If, however, the flow is reduced to say 5% the material may be compacted into briquettes, the appearance of 50 which would be practically the same as if they contained the proper amount of binder but which would be of inferior quality. The inferiority of these briquettes would ordi-

narily not be discovered until they had arrived at their destination and had been put in service.

In accordance with the present invention, I pump a much larger quantity of binder than required, from which the desired amount is drawn off for delivery to the mixing apparatus, the excess being bypassed and re-circulated through the pump. In this way, the building up of back pressures is reduced to a minimum and a more uniform and reliable flow is obtained. My invention also includes the provision of means connected with the pumping system for recording the rate of flow, so as to enable any variation to be immediately detected and proper adjustments in the valve setting to be made. 70

In the accompanying drawings forming a part hereof wherein two constructional forms of apparatus are shown, Fig. 1 is a perspective view of an apparatus, embodying the principles of my invention, and in which a manually controlled valve is employed; Fig. 2 is a side elevation showing somewhat diagrammatically an apparatus which includes an automatically controlled valve, and Fig. 3 is an enlarged cross-sectional detail of the automatic valve shown in Fig. 2.

Referring to Fig. 1 of the drawing, the numeral 10 indicates a pipe or conduit which leads to the storage tank (not shown) for the binder liquid, and which pipe is connected with the suction side of a pump 11. Connected to the delivery pipe 12 of the pump 11 is a T-coupling 13 to one branch of which is connected a by-pass conduit 14 which leads back to the suction conduit 10. Interposed in conduit 14 is a manually controlled valve 15, which in order to secure fine adjustments thereof, may be operated by a worm gearing 16 and hand wheel 17, or other equivalent means. 90

Means are provided for recording the rate of flow of the binder liquid to the mixing apparatus and such means may consist of a liquid flow indicating meter 18 of any suitable construction, connected to the delivery or pressure side of the pump 11; the liquid passing through said meter being delivered through the pipe 19 to the mixing apparatus (not shown). Secured upon the shaft of the meter 18 is a spur gear 20 meshing with 95 100

a gear 21, fastened to the armature of a small electric generator 22. The current generated by said generator is used to operate a tachometer 23 shown as supported 5 upon a rod 24 secured to the pump casing, but which may be located in any convenient place. In the installation illustrated, a recording instrument 25 is also included for recording the amount of binder used and 10 the number of briquettes made; said instrument preferably being located in the office of the plant and being operated by the current from the generator 22.

The operation of the above described installation will be readily understood. The 15 pump 11 is preferably arranged to be driven at a constant speed and to pump a greater amount of binder than is required. The excess is by-passed through the pipe 14 back 20 to the suction side of the pump. By observing the rate of the flow passing through the liquid meter 18 as indicated by the tachometer 23, the operator can determine instantly when variations in such flow occur and will 25 adjust the valve 15 as required. In the form shown in Fig. 2 the binder is drawn from the binder supply through the pipe 10^a by the pump 11^a which delivers it by the 30 pipes 12^a, and 12^b, through the meter 18 to the main delivery pipe 19. The meter 18 as also shown in Fig. 1, drives a small generator 22^a for operating the tachometer 23. Pipe 12^a has also connected thereto a branch 12^c which connects through an automatic 35 valve A and a conduit 14^a to the suction side of the pump 11^a for by-passing the excess binder back through the pump.

A suitable construction for the automatic valve is shown in Fig. 3 of the drawing and 40 consists of a central cylindrical casing 30 having the ends thereof flanged and being provided intermediate to said ends with the interiorly threaded bosses 31 and 32, to which the pipes 12^c and 14^a respectively are connected. Diaphragms 33 and 34 are clamped to the flanged ends of the casing 30 by the heads 35 and 36, said diaphragms being provided at their centers with the recessed bosses 33^a and 34^a respectively. A two-seated valve 45 37 is slidably mounted within a central cylindrical web 38, preferably cast integral with the valve casing 30, said web being provided with a pair of valve seats 39 upon which the seats 40 of the valve are adapted to engage. The valve 37 has a central rod 41, the ends 50 of which project beyond the seats 40 and are seated within the recessed bosses 33^a and 34^a. The valve casing heads 35 and 36 are provided with hollow bosses 42, 43 respectively, 55 arranged in axial alignment. The boss 43 of the lower head 36 is interiorly threaded for the connection thereto of a pipe 44 which leads to the delivery pipe 12^a for permitting the pressure of the liquid delivered by the pump to be exerted upon the lower dia-

phragm 34. The hollow boss 42 of the upper head has slidably mounted therein a rod 42^a, the lower end of which terminates in a circular flange 45 which rests upon the diaphragm 33. The upper end of said rod is 70 pointed to engage within a recess provided in a balancing beam 46; one end of said beam being pivotally mounted, as at 47, in a bracket 48, preferably formed integrally with the casing head 35, and the other end 75 of said beam having adjustably secured thereto a rod 49 upon which a plurality of weights 50 are detachably mounted.

In order to overcome pressure differences 80 in the pipe 12^a caused by variations in the head of liquid in the storage tank, or by obstructions, due to clogging of the liquid in the delivery pipe, and also to compensate for pressures above atmospheric in the suction pipe 10^a of the pump, such as would be 85 caused by having the storage tanks located at a higher level than the pump, I provide a pressure equalizing device which, as shown, may consist of a conduit 51 connected to the pipe 14^a and leading to the main delivery 90 pipe 19; said conduit 51, at its connection with the pipe 19, is provided with an equalizing diaphragm or piston valve 52.

The operation of the apparatus shown in 95 Figs. 2 and 3 is as follows: The binder liquid is withdrawn from the storage tanks through the pipe 10^a and delivered by the pump 11^a to the pipe 12^a. The pump is preferably driven at a constant speed and is adapted to 100 pump a greater supply of binder than required. The pressure of the liquid in the pipe 12^a, is communicated through the pipe 44 to the lower diaphragm 34 of the automatic valve A, and if such pressure represents the flow of a greater quantity of liquid 105 than required, as determined by the adjustment of the weights 50 upon the beam 46, the automatic valve will be opened to an amount commensurate with the difference 110 between the downward pressure exerted upon the upper diaphragm 33 by the weighted beam, and the upward pressure upon the lower diaphragm 34 communicated thereto through the column of liquid within the pipe 44. The excess binder will then be by-passed through the automatic valve and pipe 14^a to the suction side of the pump, while 115 the required amount of binder as determined by the setting of the weighted beam will pass through the liquid meter to the main delivery pipe 19; the quantity of binder passing through such meter being recorded by the tachometer 23 which is preferably calibrated in gallons per hour and is provided 120 with indicia to show the rate of flow and to register the total number of gallons which pass through the meter. If the storage tanks are located at a higher level than the pump, which is frequently the case, it is obvious 125 that the binder liquid will be delivered to

the pump under a pressure caused by the head of liquid within the pipe 10^a and the storage tanks, consequently the pressure of the liquid within the pipe 12^a will be correspondingly increased. This increase of pressure obviously will vary as the head is increased or decreased respectively by the addition and withdrawal of liquid from the storage tank. Therefore I provide the equalizing valve 50 hereinbefore referred to. If the head of the liquid is such that the pressure of the liquid passing to the suction side of the pump is, for example, equal to 20 pounds per sq. in., it is obvious, that unless some means were provided to compensate for this pressure, the proper amount of liquid would not be by-passed through the automatic valve and pipe 14^a because the flow of such liquid would be resisted by the 20 pounds pressure existing in the suction line. By connecting the pipe 51 to the pipe 14^a leading to the suction line and providing the equalizing valve 50, it will be seen that a throttling of the liquid passing through the main pipe 19 will occur; which throttling will be proportional to the movement of the equalizing valve so that a back pressure is produced in the column of liquid passing through the liquid meter, equal to the back pressure which tends to resist the passage of the excess liquid by-passed through the automatic valve. Conversely if an obstruction to the flow through the main line occurs, the resulting increase of pressure will be communicated through the equalizing valve to the by-pass line. Consequently, when the weighted beam 46 is adjusted to secure the flow of the required quantity of binder to the main line, the operation of the automatic valve will be unaffected by any pressure differences except those due to variations in the rate of flow.

It will be understood that many changes, variations, and modifications of the constructional examples herein disclosed may be resorted to without departing from the spirit of my invention.

I claim:

1. In the art of briquetting loose materials by employing a liquid binder in which such binder is withdrawn from a storage tank and delivered to a mixing apparatus to be mixed with said loose material, the steps which consist in withdrawing a larger amount of binder than is to be mixed with said loose material, regulating the amount of binder delivered to the mixing apparatus to secure the delivery of a uniform constant flow thereof according to the desired proportion of such binder to be mixed with said

loose material, and diverting the excess binder through a by-pass conduit.

2. In the art of briquetting loose material by employing a liquid binder, the step which consists in securing a uniform constant rate of feed of the liquid binder in accordance with a predetermined proportion of such binder to the loose material, characterized by pumping from the binder supply a greater amount of binder than required to maintain said predetermined proportion, delivering the proper amount of binder to be mixed with the loose material and by-passing the excess binder from the delivery to the suction side of the pump.

3. In an apparatus for the briquetting of loose material, by the use of a liquid binder which is withdrawn from a supply thereof and delivered to the place of use, a pump constructed and arranged to deliver a greater amount of said binder than required, suction and delivery conduits connected to said pump, and means to insure a constant, uniform delivery of said binder to the place of use, said means comprising a by-pass conduit through which the excess binder is circulated, connecting said suction and delivery conduits, an automatic valve for controlling the amount of binder passing through said by-pass conduit and fluid pressure actuated means to cause said valve to be operated in accordance with variations in the pressure within said delivery conduit.

4. In an apparatus for the briquetting of loose material, by the use of a liquid binder which is withdrawn from a supply thereof and delivered to the place of use, a pump constructed and arranged to deliver a greater amount of said binder than required, suction and delivery conduits connected to said pump, and means to insure a constant, uniform delivery of said binder to the place of use said means comprising a by-pass conduit through which the excess binder is circulated, connecting said suction and delivery conduits, an automatic valve for controlling the amount of binder passing through said by-pass conduit, fluid pressure actuated means to cause said valve to be operated in accordance with variations in the pressure within said delivery conduit, an equalizing valve and connections therefrom to said suction and delivery conduits for preventing differences in pressure in said suction and delivery conduits due to liquid head or obstructions from affecting the operation of said automatic valve.

In testimony whereof I have hereunto set my hand.

ELLSWORTH B. A. ZWOYER.
